F. W. HOCHSTETTER

RADIO SOUND TRANSMITTER

Filed May 1, 1923

Patented Mar. 10, 1925.

UNITED STATES PATENT OFFICE.

FREDERICK W. HOCHSTETTER, OF DAYTON, OHIO.

RADIO SOUND TRANSMITTER.

Application filed May 1, 1923. Serial No. 635,909.

To all whom it may concern:

Be it known that I, FREDERICK W. HOCHSTETTER, a citizen of the United States, and a resident of Dayton, in the county of Montgomery and State of Ohio, have invented a certain new and useful Improvement in a Radio Sound Transmitter, of which the following is a full, clear, and exact specification.

10. This invention relates more particularly to a class of devices adapted to be used as a "loud speaker" in radio-electric systems.
15. My invention has for its object primarily to provide a transmitter or loud speaker designed to be used on the receiver of radio-electric system for regulating the volume of sound aero-impulses so that the subject matter, such as musical and other phonetic compositions, when delivered to the transmitter 20 may be modulated in the course of projection to the listeners in low, medium and loud tones, and which is of a form adapted to cause the vibratory sound distributing diaphragm of the receiver to function in a manner whereby the accentuation of the subject matter rendered will be clear and distinct. The invention contemplates mainly the provision of a transmitter having a tapered annular wall with its inlet end leading from 25 the electro-magnetic sound distributing diaphragm of the radio-receiver. In the passage of the transmitter is a magnetized controller which is spaced from the diaphragm, and the controller is adjustably operative 30 for enlarging and reducing circumferentially the course leading from the diaphragm to the outlet of the transmitter whereby the volume of sound aero-impulses transmitted from the diaphragm may be regulated to cause projection of the subject matter in low, medium or loud tones as well as providing 35 clear and distinct phonetic accentuation of the subject matter by causing effectual vibratory action of the diaphragm by the magnetic influence of the controller normally attracting the diaphragm in the direction thereof.

40. A further object of the invention is to provide a radio sound transmitter of a simple, efficient and durable construction which may be made in any appropriate size and shape.

45. With these and other objects in view, the invention will be hereinafter more fully explained with reference to the accompanying drawing forming a part of this specification

in which similar characters of reference indicate corresponding parts in all the views and will then be pointed out in the claims at the end of the description.

In the drawing, Fig. 1 is a sectional view, 50 partly in elevation, taken through a radio sound receiver with one form of my device applied thereto.

Fig. 2 is an enlarged detail section, partly broken away, taken on the line 2-2 of Fig. 1 and which shows the blades of the controller of the device in partly open positions.

Fig. 3 is an enlarged sectional view taken on the line 3-3 of Fig. 1 and which shows the blades of the controller of the device in 70 closed positions, and

Fig. 4 is a view similar to the view shown in Fig. 3 and which shows the blades of the controller in open positions.

The device or transmitter has a tapered 75 annular wall 10 which may be of any suitable size as well as being of any well-known or preferred shape for serving as a "loud speaker" as is incident to the use of this class of sound amplifiers in radio-electric 80 systems. The form of the transmitter shown in the drawing has its reduced end or inlet, as 11, arcuated, and the wall of this inlet is mounted to the casing, as 12, of a radio receiver, as 13, which may be of any 85 of the ordinary types, though the receiver illustrated has on the interior of casing 10 a magnet 15, which when the device is employed in a wireless system is energized by the electric impulses transmitted over conductive wires, as 16, 17, leading from the source of sound production. Within the casing 10 in proximity to the cores of the magnet and in opposition to the inlet 11 of the transmitter is provided the usual electro-magnetic conductive diaphragm 18 90 adapted to be vibrated with the energizing of the magnet for distributing the sound aero-impulses to the transmitter for being magnified in volume during the course of 95 projection of the subject matter through and from the transmitter to the person within the range of hearing as is incident with the use of radio devices of this class.

In the inlet end of the wall of the transmitter is a magnetic controller 19 adapted to 100 be adjustably operated for regulating the volume of sound aero-impulses whereby the subject matter may be rendered in clear and distinct low, medium and loud tones. The 110

controller 19 is preferably composed of a supporting plate 20 which is fixed in the annular wall 11 of the transmitter crosswise of its passage in spaced proximity to the diaphragm 18. This supporting plate is annular in form to provide in its center a circular opening 21 the center of which is on a line corresponding with the center of the diaphragm, and in the face of the plate opposed to the diaphragm may be a recess 22 which surrounds the opening. To spaced parts of the inner edge of the annular plate 20 corresponding to the bottom of its recess is pivoted, at 23, one of the ends of a series of permanent magnets or blades 24 which are of similar sizes and shapes, and each of the blades is preferably in the form of a flat bar or plate of an approximately semi-circular shape curved substantially similar to the curvature of the edge of the opening 21 of the annular plate. There may be eight of these blades, as illustrated, and their pivots are spaced at equidistances surrounding the opening 21 so that the other portions of the blades may be swung simultaneously in overlapping positions crosswise and concentrically relative to the center of the opening as well as relative to the center of the inlet 11 for expansibly and contractibly enlarging and reducing the passage circumferentially through the transmitter 10. The blades are also of sizes so that when adjustably moved to their maximum distances toward the center of the opening 21 of the supporting plate the passage through this opening and through the inlet of the transmitter will be practically closed for cutting off the transmission of the waves of sound impulses from the diaphragm 18 through the transmitter. With the reverse adjustment concentrically of the blades the passage through the opening of the supporting plate will be enlarged accordingly for allowing proportionate volumes of the waves of sound impulses to be transmitted through the inlet 11 and through the opening of the supporting plate for projection through and from the transmitter in low, medium or loud tones. Each of the blades or permanent magnets 24 has its north pole, as *n*, pivoted to the south pole, as *s*, of the blade or magnet to which it is movably connected, in order to provide a magnetic polarity throughout all of the connected blades whereby pronounced vibratory action of the diaphragm will be accomplished by the blades forming the magnetic controller 19 tending to attract the diaphragm following each vibratory movement of the diaphragm toward the cores of the magnet 15 when energized by the electrical impulses received over the wires 16, 17. The sound aero impulses of the subject matter will thereby be rendered in clear and distinct tones by reason of the positive electro-magnetic action thus imparted to the vibratory movements of the diaphragm. Across the inlet 11 of the transmitter may be a fixed plate, as 25, in lapping arrangement on the recessed face of the supporting plate 20, and the plate 25 is also annular in form to provide in its center a circular opening 26 which is in register with as well as being similar in diameter to the opening 21 of the plate 20. In part of the face of the plate 25 surrounding the opening 26 is a recess 27 which communicates with the recess 22 of the plate 20, and both of these recesses are of like diameters. In order to permit the blades 24 to be simultaneously adjusted circumferentially in clockwise relation across the openings of the plates 20, 25 a disk, as 28, is rotatably provided in the recess 27 of the plate 25 in movable arrangement on the lapping blades 24, and in the central part of the disk is a circular opening 29 in register with as well as being of a similar diameter to the diameters of the openings 21 and 26 of the annular plates 20, 25. In equidistant parts of the edge of the opening 29 of the annular disk 28 are radially disposed slots, as 30, in each of which is slidably disposed the pin, as 31, projecting from the second end of each of the blades 24. When this disk is rotatably adjusted accordingly the pins 31 will be caused to slidably move in the slots 30 which in turn will adjustably swing the blades in unison toward and from the centers of the registered openings of the plates 20, 25 and the disk 28 for varying the circumference of the passage through the openings and through the inlet of the transmitter to permit the volume of sound aero-impulses to be regulated. Through part of the edge of the plate 25 and leading from its recess 27 as well as through part of the wall 10 of the transmitter may be a slot, as 32. On the exterior of the wall of the transmitter adjacent this slot may be provided a scale, 33, having on its exposed face equidistant indicating symbols, preferably in the forms of numerals, as 34, and each of the symbols represents a different adjustment of the disk 28 and of the blades 24 so that the circumferential positions of the blades relative to the center of the passage of the inlet of the transmitter may be determined exteriorly of the transmitter. Extending from part of the edge of the disk 28 movably through the slot 32 is an arm, or lever, as 35, having on its outer end a pointer, as 36, adapted to be moved back and forth on the scale 33 for indicating separately the symbols 34, and projecting from the lever 35 may be a handle 37 to allow manual adjustment of the lever and pointer for rotatably operating the disk and blades according to desired adjustments for modulating the volume of sound aero-impulses of the 130

subject matter rendered, as hereinbefore explained.

While in the foregoing description, I have embodied the preferred form of my invention, I do not wish to be understood as limiting myself thereto, as I am aware that modifications may be made therein without departing from the principle or sacrificing any of the advantages of this invention, therefore, I reserve to myself the right to make such changes as fairly fall within the scope thereof.

Having thus described my invention, I claim as new and desire to secure by Letters Patent:

1. In a radio sound transmitter, the combination with the electro-magnetic receiver thereof, of a magnetic controller operatively spaced from the diaphragm of the receiver for attracting the diaphragm in a direction thereto subsequent to each vibratory movement of the diaphragm to the core of the electro-magnet and said controller adjustable for enlarging and reducing circumferentially the course leading from the diaphragm to the outlet of the transmitter whereby the volume of sound aero-impulses transmitted from the diaphragm will be regulated.
2. In a radio sound transmitter, the combination with the electro-magnetic receiver thereof, of a magnetic controller operatively spaced from the diaphragm of the receiver for attracting the diaphragm in a direction thereto subsequent to each vibratory movement of the diaphragm to the core of the electro-magnet and said controller adjustable for enlarging and reducing circumferentially the course leading from the diaphragm to the outlet of the transmitter whereby the volume of sound aero-impulses transmitted from the diaphragm may be regulated, and means operative exteriorly of the transmitter for adjusting the controller according to determined adjustments.
3. In a radio sound transmitter, the combination with the electro-magnetic receiver thereof, of a magnetic controller operatively spaced from the diaphragm of the receiver for attracting the diaphragm in a direction thereto subsequent to each vibratory movement of the diaphragm to the core of the electro-magnet and said controller adjustable expansibly and contractibly relative to the center of the passage for varying circumferentially the course leading from the diaphragm to the outlet of the transmitter whereby the volume of sound aero-impulses transmitted from the diaphragm may be regulated, a scale on the exterior of the transmitter having variously positioned indicating symbols, and means operative for adjusting the controller according to the positions of the symbols.
4. In a radio sound transmitter, the combination with the electro-magnetic receiver thereof, of a permanent magnet including contacting annular disposed magnet blades pivoted crosswise interiorly of the wall and spaced from the diaphragm of the receiver for attracting the diaphragm in a direction thereto subsequent to each vibratory movement of the diaphragm to the core of the electro-magnet, said blades being simultaneously adjustable concentrically relative to the center of the passage for varying circumferentially the course leading from the diaphragm to the outlet of the transmitter.
5. In a radio sound transmitter, the combination with the electro-magnetic receiver thereof, of a permanent magnet including contacting annular disposed magnet blades pivoted crosswise interiorly of the wall and spaced from the diaphragm of the receiver for attracting the diaphragm in a direction thereto subsequent to each vibratory movement of the diaphragm to the core of the electro-magnet, said blades being simultaneously adjustable concentrically relative to the center of the passage for varying circumferentially the course leading from the diaphragm to the outlet of the transmitter, and means operative for adjusting the blades in unison according to determined adjustments.
6. In a radio sound transmitter, the combination with the electro-magnetic receiver thereof, of a fixed annular supporting plate spaced from the diaphragm of the receiver, overlapping annular disposed arcuate magnet blades each having the ends of one of their poles pivoted to the opposite pole of one of the other blades and all of the blades being in concentric arrangement adjacent the marginal edge of the opening of said plate whereby the other ends of the blades may be simultaneously adjusted concentrically relative to the center of the opening for varying circumferentially the course leading from the diaphragm to the outlet of the transmitter, and means operative for adjusting the other ends of the blades in unison according to determined adjustments.
7. In a radio sound transmitter, the combination with the electro-magnetic receiver thereof, of a fixed annular supporting plate spaced from the diaphragm of the receiver, overlapping annular disposed arcuate magnet blades each having the ends of one of their poles pivoted to the opposite pole of one of the other blades and all of the blades being in concentric arrangement adjacent the marginal edge of the opening of the supporting plate whereby the other ends of the blades may be simultaneously adjusted concentrically relative to the center of the opening for varying circumferentially the course leading from the diaphragm to the outlet of the transmitter, an annular disk rotatable on the faces of the blades opposite

to the supporting plate and the disk having in its inner edge spaced slots in each of which the second end of each of the blades is slidably pivoted, and means operative for rotatably adjusting the disk to move the blades in unison concentrically according to determined adjustments.

This specification signed and witnessed this 30th day of April, A. D. 1923.

FREDERICK W. HOCHSTETTER.
